DESIGN FOR A PITCHER OR SIMILAR ARTICLE

Frederick J. Cuthbertson, New Haven, Conn.

Application May 27, 1933, Serial No. 48,224

Term of patent 3½ years

To all whom it may concern:

Be it known that I, FREDERICK J. CUTHBERTSON, a citizen of the United States of America, and resident of New Haven, in the county of New Haven and State of Connecticut, whose post-office address is 2000 Chapel Street, have invented a new, original, and ornamental Design for a Pitcher or Similar Article, of which the following is a specification, reference being had to the accompanying drawing, forming part thereof,

In the drawing, Figure 1 is a side elevational view of the article embodying my design. Figure 2 is a detail plan view of the ornamentation shown on the article illustrated in Figure 1.

I claim:

The ornamental design for a pitcher or similar article, as shown and described.

FREDERICK J. CUTHBERTSON
